ATTORNEY.

UNITED STATES PATENT OFFICE

WALTER VON NESSEN, OF NEW YORK, N. Y., ASSIGNOR TO EFCOLITE CORPORATION, OF TRENTON, NEW JERSEY

ELECTRIC LIGHTING FIXTURE

Application filed November 7, 1930. Serial No. 493,987.

My invention relates to improvements in electric lighting fixtures and has reference particularly to a side wall fixture consisting of a wall bracket and removable shade 5 therefor.

The invention has for its object to provide an electric side wall lighting fixture having a demountable shade and novel means for making the connection between 10 the shade and supporting bracket.

A still further object of my invention is to provide detachable connecting means for a shade, which is removable from its bracket for purposes of changing a bulb and for 15 cleaning, and which is self-positioning with respect to its supporting bracket.

I accomplish these objects by means of certain constructions and combinations of parts hereinafter described, set forth in the 20 appended claims and illustratively exemplified in the accompanying drawing, in which Figure 1 is a perspective view of the wall bracket forming the support for the shade, part of the bracket being broken away; 25 Figure 2 is a rear perspective view of the shade; Figure 3 is a perspective view of the assembled fixture with parts broken away to illustrate the means of detachably mounting the shade upon the bracket; and 30 Figure 4 is a perspective view of a portion of the wall bracket in slightly modified form, and upon which the shade is supported, part of the bracket being shown in section to illustrate the retaining head and channel 35 therein. Figure 5 is a substantially longitudinal sectional view of a portion of the bracket and shade showing a modified arrangement of certain details of construction.

Referring to the drawing, 10 denotes a 40 wall bracket comprising in the present instance a box like portion adapted to fit with its rear open side against a side wall. The box is fastened to the wall in any well known manner and houses any portion of 45 the wall box and conduit wires forming part of the installation. Projecting from the closed front wall 11 of the box at a point preferably on a vertical center line and closely adjacent the top or upper end 50 thereof is an integral neck portion 12 termi-

nating at its outer end in a flanged head portion 13. The head 13 is preferably rectangularly shaped with sides disposed upright and the top and bottom sides at right angles thereto. The center of the head 13 55 and neck 12 is provided with a depression or socket 14 into which the electric bulb (not shown) is accommodated, the screw base of the bulb projecting through an orifice 15 in the inner wall of the socket 14, 60 as illustratively exemplified in Figure 1. The top and sides of the head 13 are flanged front and back with an intervening groove 16. In Figure 4 the bottom of groove 16 65 along the upright sides of the head is curved inwardly slightly from the ends towards the centers, for the purpose herein-after described.

As will be readily understood, the foregoing wall bracket, after being properly installed and provided with a bulb inserted in the usual manner, is in readiness to receive its shade. The shade 17 in the present case comprises an enclosure having an open side to fit over the neck and head of the 70 bracket 10 and an adjacent back wall 18 having a rectangular opening 19 opening into the open side of the shade. The dimensions of the opening 19 correspond substantially with the dimensions of the bottom 75 walls of the groove 16, so that when the open end of the opening 19 is placed over the head 13, the side walls of the opening will be accommodated in the upright grooves 16 80 and the shade may be lowered until the closed end of the opening 19 rests in the top or lateral section of the groove 16. In 85 this manner the shade is supported in substantially rigid position against tilting in any direction with respect to the bracket. 90

The present invention is particularly adaptable for what are known as porcelain fixtures which are provided with colored glazed surfaces. The glazing is applied in any well known manner as for example by 95 a dipping process which of course brings the coating into the groove 16 as well as to other parts of the fixture. As a consequence, the dimensions of the grooves 16 are often reduced by an accumulation of the 100

hardened glaze and the sides of the opening 19 bind when being inserted into the grooves.

With the foregoing in mind, it is contemplated to curve the bottom walls of the grooves 16 inwardly from ends or corners toward the centers so that the sides of the shade opening 19 will only engage in the grooves at the corners as illustratively exemplified in Figure 4.

Having now described my invention, what I claim and desire to secure by Letters Patent of the United States is:

1. A lighting fixture of the character described comprising a wall bracket provided with a forwardly projecting angular neck portion terminating in an upright flanged head, the flanges being spaced from each other about the top and sides of the head to form a groove, and a shade comprising a hollow member having an open bottom and a rectangularly shaped cut out portion in the back wall corresponding approximately in dimensions with those of the bottom of the groove, whereby the latter will accommodate the sides and closed end of the cut out portion to removably support the shade with respect to the bracket.
2. A lighting fixture, as claimed in claim 1, in which the neck portion and head is provided with a tapered socket and orificed inner wall to accommodate a bulb, substantially as described.

In testimony whereof he has affixed his signature.

WALTER VON NESSEN.
